DAVID K. BEACH AND IRVING A. TAYLOR, OF WORCESTER, MASSACHUSETTS, AS
SIGNORS TO RILEY STOKER CORPORATION, A CORPORATION OF MASSACHUSETTS.

DRIVING MECHANISM FOR CLINKER GRINDERS.

Application filed June 12, 1922. Serial No. 567,600.

This invention relates to driving mechanism for a clinker grinder in a furnace and particularly a mechanism for automatically controlling the period of movement thereof.

5 In the operation of furnaces having mechanical stokers equipped with clinker grinders, it is commonly desirable to rotate the grinder mechanism periodically to an extent sufficient to remove the surplus ashes but not 10 sufficient to uncover the grinding roll or rolls and expose them to the heat of the furnace.

It is the object of our invention to provide driving mechanism having a period of movement which may be selectively determined and by which the roll will be given a 15 definite angular movement, after which it will remain at rest until again placed in operation by the use of a manual starting device.

20 With this general object in view, important features of our invention relate to improved ratchet driving mechanism for a clinker grinder, to devices for selectively determining the period of movement thereof, 25 to devices for manually controlling the starting of the mechanism, and to arrangements and combinations of parts which will be hereinafter described and more particularly pointed out in the appended claims.

30 A preferred form of our invention is shown in the drawings in which:

Fig. 1 is an end elevation of our improved driving mechanism, with certain parts broken away to disclose other parts;

35 Fig. 2 is a side elevation of the parts shown in Fig. 1;

Fig. 3 is a sectional plan view taken along the line 3—3 in Fig. 1; and

Fig. 4 is a sectional bottom view taken 40 along the line 4—4 in Fig. 1.

Referring to the drawings, we have shown a portion of a side wall 10 of a furnace and also of the floor 11 of the furnace room. A clinker grinder roll 12 having 45 grinding teeth or projections 12^a is mounted in the usual bearings 13, one of which is shown in Fig. 2. The parts of the furnace and stoker are commonly so disposed that the grinder roll is below the level of the floor, 50 although this location is not essential.

For the purposes of rotating the roll 12, we secure a ratchet wheel 14 thereto in any convenient manner as by bolts 15. A second ratchet wheel 16 is mounted to rotate freely 55 upon the hub of the ratchet 14 and a sprocket

wheel 17 is keyed or otherwise secured to the hub of the loose ratchet wheel 16. A pair of ratchet pawls 18 and 19 are provided for the ratchet wheels 14 and 16, said pawls being preferably mounted upon a bolt 20 supported 60 in a swinging frame 21. The frame 21 is formed of side plates 22 and 23 freely movable about the axis of the roll 12 and secured in spaced relation by bolts 24 and bushings 25. A link 26 connects the swinging frame 65 21 to any suitable reciprocating element of the stoker mechanism, such as the coal feeding ram or the reciprocating retort side walls.

A chain 27 connects the sprocket wheel 17 to a second sprocket wheel 28 mounted upon 70 a bearing 29 fixed to the furnace wall 10. The sprocket wheel 28 is provided with a handle 30 by which it may be manually rotated.

A shield 31 (Fig. 1) is provided for the 75 pawl 19 and a similar shield 32 (Fig. 2) is provided for the pawl 18. These shields are mounted on blocks or plates 33 and 34 which are provided with segmental slots through which extend bolts 35 which guide the plates 80 and shields for movement about the axis of the roll 12. The shield plates 33 and 34 are pivoted to links or controlling devices 36 and 37 which extend upward through the floor 11 and through a slotted base plate 38. Each 85 link is provided with a handle at its upper end and also with a plurality of holes extending therethrough and positioned to receive a pin or stud 39 in the base plate 38. By removing the pin, the links 36 and 37 90 95 may be adjusted vertically as desired and the shields 31 and 32 may thus be held in any desired position relative to the pawls 18 and 19.

The number of teeth in the ratchet wheels 95 14 and 16 may be varied to suit different operating conditions. As shown herein, the wheel 14 is provided with a relatively small number of large teeth spaced widely apart while the ratchet wheel 16 has a much larger 100 number of smaller teeth. The wheel 16 also has a blank portion 40 which is preferably of greater thickness than the toothed portion of the wheel, thus providing a shoulder (Fig. 4) adapted to pass under and engage 105 a lug 41 on the side of the pawl 18.

Having described the details of construction of our improved driving mechanism, the operation thereof is as follows:

The shields 31 and 32 are first set to per- 110

mit the desired advance movement of each wheel at each feeding motion of the pawls 18 and 19, caused by the oscillation of the swinging frame 21. For the purposes of illustration, it may be assumed that the freely rotating ratchet wheel 16 has fifty ratchet teeth and a blank portion equal to ten teeth, while the ratchet wheel 14 fixed to the roll 12 has fifteen teeth. We may also assume that 5 the shields are arranged so that the pawl 19 will feed the ratchet wheel 16 two teeth for each oscillation and that the pawl 18 will feed the ratchet wheel 14 one tooth. The ratchet wheel 14 and the roll 12 will thus be 10 angularly advanced twice as fast as the ratchet wheel 16. After the wheel 16 has been advanced somewhat less than a full revolution, the portion 40 thereof will engage and lift the pawl 18 and thus stop the 15 feed of the wheel 14 and the roll 12. At approximately the same time the feed pawl 19 will engage the uncut surface of the wheel portion 40, thus preventing further movement of either ratchet wheel after the clinker 20 grinder roll has made approximately one and three quarters revolutions.

By changing the number of teeth in the ratchet wheels or the number of teeth fed at each stroke, the number of revolutions may 30 be widely varied, so that the roll 12 may be stopped after several revolutions or after a fraction of a revolution, as may be desired. The parts, when once stopped, will remain 35 at rest until the operator rotates the ratchet wheel 16 by means of the handle 30 and chain 27 to remove the portion 40 from engagement with the feed pawls, thus permitting further advance movement of the ratchet wheels.

40 Several important advantages arise from the use of our improved driving and controlling mechanism. It is impossible with this mechanism for an operator to leave the grinding roll rotating for an indefinite period, removing all of the ashes and exposing the roll to the heat of the furnace by which it would be quickly distorted and ruined. Furthermore, the time of the operator is saved, as it is merely necessary for him to start the clinker grinder in operation and he can then go about other work, knowing that the grinder roll will come to rest after the desired activity. The device is 45 also readily adjustable to different conditions of furnace operation, as the period of rotation of the roll may be varied within wide limits.

Having thus described our invention and 60 the advantages thereof, we do not wish to be limited to the details herein disclosed otherwise than as set forth in the claims, but what we claim is:—

1. In a furnace, a clinker grinder roll, means for rotating said roll, means to stop 65 the roll after a predetermined movement

thereof, and means to vary both the rate and extent of said movement.

2. In a furnace, a clinker grinder roll and driving mechanism therefor, said means including a ratchet wheel connected to said roll, actuating means to give said wheel a limited angular movement of predetermined extent, means to render the driving mechanism inoperative at the completion of such predetermined movement and manual means 70 to render said driving mechanism again operative.

3. In a furnace, a clinker grinder roll and driving mechanism therefor, said means including a ratchet wheel connected to said 80 roll, means to give said wheel a limited angular movement of predetermined extent, and means to vary the extent of said movement.

4. In a furnace, a clinker grinder roll and 85 driving mechanism therefor, said means including a ratchet wheel connected to said roll, means to give said wheel a limited angular movement of predetermined extent, and means to vary the rate and extent of 90 said movement.

5. In a furnace, a clinker grinder roll, driving mechanism therefor including a ratchet wheel connected to said roll, means to rotate said ratchet wheel and roll, automatic means to render said rotating means inoperative after a limited angular movement of predetermined extent, means to vary the limit of such movement, and manual means to render said driving mechanism 100 again operative.

6. In a furnace, a clinker grinder roll, driving means therefor including a ratchet wheel fixed to said roll, stopping means therefor including a second ratchet wheel loosely mounted on said roll, separate feed pawls for said ratchet wheels, and separate means to adjust the effective stroke of each pawl.

7. In a furnace, a clinker grinder roll, 110 driving means therefor including a ratchet wheel fixed to said roll, stopping means therefor including a second ratchet wheel loosely mounted on said roll, and having teeth on a portion only of its periphery, 115 separate feed pawls for said wheels, and means on the second ratchet wheel effective in a certain position thereof to render inoperative the feed pawl for the ratchet wheel fixed to the grinder roll.

8. In a furnace, a clinker grinder roll, driving means therefor including a ratchet wheel fixed to said roll, stopping means therefor including a second ratchet wheel loosely mounted on said roll, separate feed 125 pawls for said ratchet wheels, a shield for each pawl, and manual means to adjust said shields.

9. In a furnace, a clinker grinder roll, driving means therefor including a ratchet 130

wheel fixed to said roll, stopping means therefor including a second ratchet wheel loosely mounted on said roll, separate feed pawls for said ratchet wheels, a shield for each pawl, and manual means to adjust said shields, said shields having segmental slots concentric with said roll and being slidable upon supporting devices extending through said slots.

10 10. In a furnace, a clinker grinder roll, means to rotate said roll, a limit device effective to disable said rotating means after

a predetermined rotation of said roll effective to remove the surplus ashes while said roll remains covered, and means to manually 15 and selectively adjust said limit device to vary the extent of rotation of said roll and to adapt the amount of rotation to meet the operative load conditions.

In testimony whereof we have hereunto 20 affixed our signatures.

DAVID K. BEACH.
